INFANT'S BATHING AND DRESSING STAND

Leonard W. Schwartz, Henrietta, N. Y.

Application April 14, 1947, Serial No. 741,172

9 Claims. (Cl. 4—173)

1

The present invention relates to folding type infant's bathing devices and particularly to a folding stand having both a bathtub and a dressing support. More specifically the invention relates to a folding stand in which the dressing support is adapted to overlie the bathtub when in use and is adapted to be out of the way when the bathtub is being employed, and in which foot treads or similar operating devices are provided to permit movement of the dressing support both into and out of position for use.

Several different forms of folding type infant's bathing devices are known. Usually, the tub is made of canvas or some suitable flexible waterproof material, and folds when the stand is folded. After they have been used for some time, these tubs develop cracks and leaks with repeated folding, and have frequently to be replaced.

In some types of stands the support, on which the infant may be laid while dressing it, is in the form of a rigid frame with a flexible top, and this dressing support or table has to be moved bodily from an inactive position at the rear and behind the tub to an active position overlying the tub. Such a table is awkward and cumbersome to handle and in some instances positively dangerous, for, if the foot treadle, which operates it were to be accidentally tripped while an infant was in the tub, the frame of the table might strike the infant on the head and injure it seriously. In other types of stands, the dressing support is in the form of a flexible sheet which is supported at its front and rear and is stretched to overlie the tub for use and is flopped over the back of the stand when not in use.

Ordinarily, a guard is provided at the back of the stand at the top thereof to prevent the baby from rolling off the dressing table when the table is being used, and commonly pockets are provided in the guard for talcum powder, safety pins, and similar infant accessories. With known types of stands, the guard and whatever accessories are carried thereon, are inaccessible when the dressing table is not in use, and cannot be used when the baby is in the tub.

Some previous types of folding stands have been equipped with towel racks, but the space available for towels is quite limited. For this reason it has been customary for the parent to purchase a so-called utility stand as a separate article of furniture for use as an accessory to the infant's bathing device. Extra towels, diapers, etc. are placed on this utility stand to be accessible to the mother in dressing the baby.

One object of the present invention is to provide a folding infant's bathing stand having a

2

support on which the baby may be laid while it is being dressed, which will be completely safe and with which any possibility of the baby being injured by the dressing support falling on it is eliminated entirely.

Another object of the invention is to provide a device of the character described in which the dressing support is constructed as to be compact and completely out of the way when the tub is being used.

Another object of the invention is to provide a dressing support which can quickly and easily be manipulated by foot treads to move it to and from position for use.

A further object of the invention is to provide a device of the character described in which the dressing support is so constructed and mounted that the guard and the various toilet articles and accessories carried thereon will readily be accessible to the mother both when the tub is in use and when the dressing support is in use.

Another object of the invention is to provide a dressing support for a device of the character described which is so constructed that it will be held rigidly and will not collapse when in use.

A further object of the invention is to provide a device of the character described which has a plurality of racks for towels, diapers, etc. so that the need for a separate utility stand is obviated.

A further object of the invention is to provide a device of the character described in which the towel and diaper holders, when in use, act as auxiliary means preventing collapse or accidental folding of the stand.

Still another object of the invention is to provide a folding stand of the character described which will be much more rigid in construction than any device of this nature heretofore built, and which at the same time will be relatively inexpensive.

A still further object of the invention is to provide a folding type infant's bathing stand in which the tub may be constructed of a light weight metal, such as aluminum, and will never wear out.

Another object of the invention is to provide a folding type infant's bathing stand in which the tub is detachable from the stand and transportable, so that it can be lifted out of the stand and carried to a sink to fill it or to empty it, and the necessity for using separate filling or emptying vessels is obviated.

Other objects of the invention will be apparent hereinafter from the specification and from the recital of the appended claims.

In the drawings:

Fig. 1 is a perspective view of a combined tub and dressing support built according to one embodiment of this invention, the dressing support being shown in position for use;

Fig. 2 is a side elevation of the combined tub and support, showing the dressing support in full lines in completely folded position and in dotted lines in partially open position;

Fig. 3 is a fragmentary perspective view similar to Fig. 1, but showing the towel and diaper rack at one end of the stand in operative position;

Fig. 4 is a perspective view of one of the towel and diaper racks;

Fig. 5 is a fragmentary front elevational view and Fig. 6 a fragmentary side elevation view, on an enlarged scale, showing one of the foot treads in two different positions and illustrating its operation;

Fig. 7 is a fragmentary perspective view on an enlarged scale, showing a detail of the structure of the legs of the supporting stand;

Fig. 8 is a fragmentary sectional view on an enlarged scale on the line 8-8 of Fig. 2, showing further details of the leg structure and of the mounting of one of the clips which holds the free end of one of the towel racks, when the stand is folded;

Fig. 9 is a perspective view and Fig. 10 is a section on an enlarged scale, showing further details of the structure of the legs and of the way the cross-rods, which connect the legs, are secured thereto;

Fig. 11 is a side elevation, with parts broken away, of a folding stand made according to another embodiment of this invention;

Fig. 12 is a side elevation, showing this stand folded; and

Fig. 13 is a perspective view of the tub used with this stand.

Referring now particularly to the modification of the invention shown in Figs. 1 to 6 inclusive, the device includes a foldable stand comprising a pair of front legs 20 and a pair of rear legs 21. The legs are pivotally connected intermediate their ends by a longitudinally extending rod or bar 22. The front legs 20 are connected at their upper ends by a longitudinally extending rod or bar 24, and adjacent their lower ends by a longitudinally extending rod or bar 25. The rear legs are connected at their upper ends by a longitudinally extending rod or bar 26 and adjacent their lower ends by a longitudinally extending rod or bar 27. The tub 30, which in this embodiment of the invention is made of rubber or canvas, or other suitable water-proof material, is adapted to be suspended in the usual manner from the bars 24 and 26.

The support 35, on which the infant may be placed while it is being dressed, comprises a piece of flexible, water-proof material, such as canvas or rubberized fabric. This is secured at one end to a rod 36 which is mounted in the legs 20 of the supporting structure above the bar 24 which carries the rear end of the tub 30. This rod 36 is built like a curtain rod or roller with an internally mounted spring (not shown) so as to automatically wind the flexible support 35 upon it. The forward end of the flexible support 35 is looped around and secured to a rod 37 which is journalled in the upper ends of two parallel arms 38 that are pivotally mounted at their lower ends on the longitudinal bar 22.

The support 35, when in use, is adapted to over-

lie the tub 30, as shown in Fig. 1. When the tub is being used, however, the support 35 is wound up on the roller 36 and the tub is completely clear. To remove the support 35 from rolled-up position to extended position and vice versa, foot treads 39 and 40 are provided. The foot treadle 39 is made of flat stock, which is bent, as denoted 41 (Fig. 6), over the bar 25 and has a downwardly extending leg 42, which is bent around a rod 44. The rod 44 is secured at opposite ends to the legs 45 of the U-shaped foot treadle member 40. These legs 45 are bent outwardly at their upper ends and secured in the links 46 of two folding braces 50, whose other links are denoted at 47. The links 46 and 47 of each brace are pivotally connected to one another by means of pin 48. Each link 46 is pivotally connected at its front end at 49 (Fig. 2) to one arm 38 intermediate the ends of that arm, and each link member 47 is pivotally connected at its rear end by means of a pin 51 to the leg 20 intermediate the bar 22 and the bar 24.

Fig. 1 shows the stand opened up with the dressing support 35 extended over the tub 30 for use. The braces 50 are extended and serve to prevent collapse of the support 35 under the weight of the infant, lugs 52 being provided on each link member 46 to engage the cooperating link 47 to prevent the braces from folding.

To roll up the dressing support 35, the mother only needs to step on the foot treadle 39. This will move the foot treadle from the full-line position shown in Figs. 5 and 6 to the dotted-line position 39' of that figure, causing the braces 50 to fold, and allowing the spring in the roller 36 to automatically wind-up the dressing support 35. Fig. 2 shows the support partially wound up in dotted lines and completely wound up in full lines. In the movement of the dressing support to wound up position, the legs 45 of foot treadle 40 move from the position shown in Fig. 1 through the dotted-line position of Fig. 2 to the full-line position of the latter figure. The several parts are denoted in dotted lines by the same reference numerals as employed in full lines except that the numerals are primed.

To extend the dressing support again, the mother need only step on the treadle 40 which is at the moment in the full-line position shown in Fig. 2. At this time, the legs 45 of treadle 40 bear on bar 22, and as the treadle 40 is stepped on, the bar 22 is initially a fulcrum for the arms 45. As the treadle 40 is further pressed down, the treadle and its legs 45 are moved forwardly from the position shown in full lines in Fig. 2 through the dotted-line position in Fig. 2 to the full-line position of Fig. 1, during the course of which movement the arms 38 will be moved from the full-line position shown in Fig. 2 through the dotted-line position shown in that figure to the full-line position shown in Fig. 1. Thus, with a folding stand built according to this invention, the mother or nurse can hold the infant with both hands while employing her foot to cause the dressing support to be moved to extended position or to be rolled up.

The length of sheet 35 is selected so that when it is extended, braces 50 in their fully open position will stretch it taut. Thus, sheet 35 provides a suitable support on which the infant may be placed while it is being dressed or undressed.

Mounted in the upper ends of the legs 20 are the downwardly projecting legs 55 of a frame whose upper portion is bent rearwardly as denoted at 56. This frame carries the guard 57 and

a shelf 58. Various toilet and bath accessories may be placed on the shelf 58. It will be noted that these are available to the mother or nurse, both while the infant is being bathed and while it is being dressed, for the dressing support 35 rolls up entirely out of the way beneath guard 57 when the tub 30 is in use.

The usual towel rack 60 (Fig. 1) may be secured in the upper ends of the legs 21. In addition, however, I have provided with the present invention auxiliary side racks 65 (Figs. 3 and 4) on which may be carried a complete supply of towels, diapers, and baby clothing. There are two of these auxiliary racks, one at each end of the stand. The right-hand rack only is shown in the drawings, but the two racks may be identical in construction except that one will be right-hand and the other left-hand. Each consists of a U-shaped frame one leg 66 of which is longer than the other leg 67. The free ends of the legs 66 and 67 are adapted to be inserted, when the stand is open, in elongated holes formed in the ends of the rods 24 and 26, respectively. The ends of the legs 66 and 67 are turned upwardly as denoted at 68 and 69, respectively, the upturned ends serving as stops to prevent complete withdrawal of the racks from the supporting stand unless the racks are first rocked upwardly. The shorter leg 67 of each rack is withdrawn first. This permits the rack to be swung down to inoperative position, when the stand is folded, that is, to the position denoted at 65' in dotted lines in Fig. 3.

Keepers 72, each of which has a hole 73 in its free end, are secured to the legs 20 and 21 at their pivot points, as will be described further herein-after. The leg 67 of each rack is adapted to be slid into a hole 73 to hold the rack in inoperative position. This is the position occupied by the racks 65 when the stand is folded.

Mounted to slide on the legs 66 and 67 of each rack 65 are a plurality of parallel cross-rods or bars 70. The rods or bars 70 sliding along the legs, permit virtually complete telescoping of the racks into the legs 20 of the stand when the stand is folded. Thus, the racks may be completely out of the way. When the stand is open, however, and the two legs 66 and 67 of the racks are engaged in the two bars 24 and 26, each rack can be pulled out until upturned end 69 of leg 67 stops the outward movement. When rods 70 are separated, then, all the towels and diapers required can be suspended on the racks. The racks 65 together with shelf 58 (Fig. 1) render unnecessary the procurement of a separate utility stand. Moreover, when the stand is open and the legs 66 and 67 of the racks are engaged in the bars 24 and 26, the racks act as auxiliary means for holding the stand in its open position, and for preventing possible collapse of the stand. A pair of chains 120, each of which is secured at opposite ends to the legs 20 and 21 of a pair, prevent the stand from being opened too far.

One feature of the present invention is the construction of the stand or frame itself. A much more rigid, sturdy construction has been provided than in devices of this character as previously built. The legs of a stand built according to the preferred embodiment of this invention are made of sheet metal stamped into shape and welded together and the cross-bars can be made of seamless tubing welded to the legs. In the preferred construction, each leg comprises two pieces of sheet metal 80 and 81 (Figs. 7, 8 and 9). The pieces 81 are reversely bent to form two ribs 82

and 84 and an intermediate central depression or channel 85. The sides of the ribs converge slightly toward their tops. The lateral ends of the piece 81 are bent backwardly to U-shape as denoted at 86 and 87, respectively. The piece 80 is generally flat, but has its lateral ends 88 and 89 also bent over one another inwardly into U-shape so that they can be interfitted with the U-shaped portions 86 and 87 of a meshing piece 81, and the two pieces 80 and 81 of a leg telescoped into one another.

Fig. 8 shows the structure at the point of pivot of two of the legs. Between the two legs there is interposed a circular washer 95 and the keeper 72 which, as above described, is used to hold one of the towel racks 65 when the stand is folded. This keeper is formed with a rib 96 which is shaped to fit into the depression or channel in the part 81 of the leg 20. The two legs are connected by a headed pivot stud 97. A washer 98 is interposed between the flat side of the leg 20 and the nut 99 which threads onto this pivot stud. The pivot stud itself threads into the solid cylindrical pivot bar 22 and a washer 100 is interposed between the nut 99 and the adjacent end of the bar.

The bars 24, 26, 25 and 27 are preferably made of seamless tubing which is welded to the legs. Figs. 9 and 10 show the upper end of one leg 21 and how the bar 26 is secured thereto. The other bars are connected at their two ends to the legs in this same manner. The side piece 80 of the leg is stamped or pressed to form a reinforcing beading 106 and a centering collar 107. The tube 26 is adapted to be slipped over this collar 107 and has its end bent outwardly, as denoted at 108. After the tube is in position, tube, centering collar and leg are welded together.

Reinforcing strips 90 are provided at the tops of legs 20. These fit into the channels 85 of the leg parts 81 and are drilled to receive the legs 66 (Fig. 7) of the towel racks 65. One such strip is further slotted to receive the squared end 91 of roller 36.

Cap members 105 of suitable shape are provided to close the upper and lower ends of the legs, and provide a neat design.

The legs are all made alike. To avoid having too many lines in the drawings, the detail structure of the legs is not shown, however, in Figs. 1 and 3.

The embodiment of the invention illustrated in Figs. 11 to 13 inclusive may be made exactly the same as that already described except for the tub. In the embodiment shown in Figs. 11 to 13, the tub 110 is made of aluminum or some other suitable light-weight material. This tub may be stamped or pressed into shape. Along both its front and rear sides it has downturned portions 111 and 112 which form hooks by which the tub may be suspended from rods 24 and 26 when the stand is open. The tub is made of a height to lie beneath dressing support 35 when the latter is open and in use, as shown in Fig. 11.

When the stand is to be folded, the tub 110 does not fold. Instead it is lifted out and suspended by hook portion 111 or 112 from rod 26 or rod 24. It will swing into the opening between the two pairs of legs and will be out of the way, as shown in Fig. 12. Here, the tub is shown hanging by hook portion 112 from bar 26.

To avoid sharp edges the sides of the tub are turned down at their tops as indicated at 113 and 114. The bottom 115 of the tub may be sloped to one side of the tub to permit easy drain-

age and a hose connection 116 may be provided through which the water may be discharged.

The aluminum tub, especially when made from a stamping, is cheaper than a canvas or rubber tub. It will not wear out. Moreover, it is so light that it can easily be picked up and carried even when filled with water. Hence it can be taken to or from the sink for filling or emptying. It is not necessary, as has been the case in the past, to carry a pot or kettle back and forth between sink and tub to fill or empty the tub.

A stand constructed according to either of the described embodiments of the invention is rigid, sturdy, convenient and relatively inexpensive. The invention is capable of still further modification, and it will be understood that this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. The combination with a folding stand comprising two longitudinally-spaced pairs of front and rear legs, means pivotally connecting the pairs of legs together so that they may be opened or closed, and longitudinally extending bars connecting the front and rear legs at their tops and adapted to support a tub, of a roller mounted on the rear legs, a flexible sheet secured at one end to said roller, said roller having means incorporated therein for automatically winding up the sheet thereon, a longitudinally extending rod to which the free, forward end of the sheet is attached, and a pair of arms, each of which is connected at one end to one end of the rod, and each of which is pivotally connected at its opposite end to the stand to pivot about the same center as the legs of the stand.

2. The combination with a folding stand comprising two longitudinally-spaced pairs of front and rear legs, means pivotally connecting the legs together so that they may be opened or closed, and longitudinally extending bars connecting the front and the rear legs at their tops and adapted to support a tub, of a roller mounted on the rear legs, a flexible sheet secured at one end to said roller, said roller having means incorporated therein for automatically winding up the sheet thereon, a longitudinally extending rod to which the free, forward end of the sheet is attached, a pair of arms, each of which is connected at one end to the rod, and each of which is pivotally mounted at its opposite end on the stand to pivot about the same center as the legs of the stand, a pivoted brace connecting each arm with one of the legs of the stand, and foot-operated means connected to the braces for opening and closing the braces to cause the sheet to be extended or to permit it to be wound upon the roller.

3. The combination with a folding stand comprising two longitudinally-spaced pairs of front and rear legs, means pivotally connecting the legs together so that they may be opened or closed, and longitudinally extending bars connecting the front and the rear legs at their tops and adapted to support a tub, of a roller mounted on the rear legs, a flexible sheet secured at one end to said roller, said roller having means incorporated

therein for automatically winding up the sheet thereon, a longitudinally extending rod to which the free, forward end of the sheet is attached, a pair of arms, each of which is connected at one end to the rod, and each of which is pivotally mounted at its opposite end on the stand to pivot about the same center as the legs of the stand, a pivoted brace connecting each arm with one of the legs of the stand, a pair of foot treadles, and means operatively connecting the two treadles with the brace so that, when one foot treadle is stepped upon, the brace is opened to extend the sheet, and when the other foot treadle is stepped upon the brace is folded to permit the sheet to be wound upon the roller.

4. The combination with a folding stand comprising two longitudinally-spaced pairs of front and rear legs, means pivotally connecting the pairs of legs together at a point intermediate their ends so that they may be opened or folded, and two longitudinally extending bars connecting the front and the rear legs at their tops and adapted to support a tub, of a rigid, one piece, U-shaped rack one of whose free ends is pivotally mounted in aligned holes formed in one of the bars and one leg, and the other of whose free ends may be mounted in aligned holes formed in the other bar and a leg when the legs are swung open, and the rack is swung to operative position, said rack, when so mounted in operative position, being adapted to hold the legs open and prevent accidental pivotal closing movement thereof.

5. The combination with a folding stand comprising two longitudinally-spaced pairs of front and rear legs, means pivotally connecting the pairs of legs together at a point intermediate their ends so that they may be opened or folded, and two longitudinally extending bars connecting the front and the rear legs at their tops and adapted to support a tub, of a towel rack having means thereon for supporting towels and mounted on one of said bars and adapted to be swung to a position to engage the other bar, also, when the legs are open, to hold the legs open and prevent accidental pivotal closing movement of the legs.

6. The combination with a folding stand comprising two longitudinally-spaced pairs of front and rear legs, means pivotally connecting the pairs of legs together at a point intermediate their ends so that they may be opened or folded, and two longitudinally extending bars connecting the front and the rear legs at their tops and adapted to support a tub, of a rigid, one piece, U-shaped rack, one of whose free ends is mounted in aligned holes in one of the two bars and one leg, and a keeper, which is secured to one of the legs, said keeper having a hole therein into which the other free end of said rack is adapted to be engaged when the stand is folded, the other bar and cooperating leg having aligned holes into which the latter free end of the rack may be mounted, when the stand is open, to hold the rack in operative position and also to prevent accidental collapse of the stand.

7. The combination with a folding stand comprising two longitudinally-spaced pairs of front and rear legs, means pivotally connecting the pairs of legs together at a point intermediate their ends so that they may be opened or folded, and two longitudinally extending bars connecting the front and the rear legs at their tops and adapted to support a tub, of a rigid, one-piece towel rack of U-shape, one of whose legs is shorter than the other, the two bars having holes

therein at one end and the adjoining legs of the stand having aligned holes therein, one set of aligned holes being adapted to receive the longer leg of the rack, the other set of aligned holes being adapted to receive the shorter leg of the rack, when the stand is open to hold the rack in operative position and also to prevent accidental collapse of the stand, and a keeper fastened to the stand to hold the shorter leg of the rack when the stand is folded to keep the rack from swinging.

8. The combination with a folding stand comprising two longitudinally-spaced pairs of front and rear legs, means pivotally connecting each pair of legs at a point intermediate the ends of the legs, a bar extending longitudinally between the two pivot points, and two other longitudinally extending bars connecting the front legs and the rear legs, respectively, adjacent their tops, of a rigid tub, said tub being provided with hook-shaped hangers at front and rear by which said tubs may be suspended from the last two named rods in horizontal position when the stand is open, said tub being of a width less than the distance between either of the two top bars and the bar which extends between the pivot points, whereby the tub may be suspended by one of its hangers from one of said two last named rods in approximately vertical position when the stand is folded, and a dressing support connected to the rear legs at their tops and movable from an inoperative position at the rear of said stand to an operative position overlying said tub.

9. The combination with a folding stand comprising two longitudinally-spaced pairs of front and rear legs, means pivotally connecting the pairs of legs together so that they may be opened or closed, and parallel longitudinal bars connecting the front and rear legs at the tops thereof and adapted to support a tub, a dressing support comprising a flexible sheet, a roller to which one

end of the sheet is secured, said roller being mounted on the rear legs of the stand and having means incorporated therein to wind up said sheet automatically, and means for moving the sheet from wound-up position to extended position overlying said tub, and vice versa, a bracket mounted on the tops of the rear legs above said roller, and a rack supported for swinging movement from one of said bars and having a free end adapted to be mounted on the other of said bars when the stand is open to hold the rack in operative position and also to connect the two legs so that they are prevented from being accidentally folded.
